BRIQUETTING MACHINE

Robert T. Bowling, Lewiston, Idaho, assignor, by
mesne assignments, to Wood Briquettes, Inc.,
Lewiston, Idaho

Application December 23, 1932, Serial No. 648,603

18 Claims. (Cl. 25—12)

My present invention relates to an improved briquetting machine or press, for molding solid cylindrical briquettes from sawdust, wood shavings, vegetable fibers, etc. The machine is of the 5 type utilizing a tapered feed screw which forces the material through a stationary die into a cylindrical mold against the resistance of a hydraulically yielding or receding die, and means are provided for varying the hydraulic resistance 10 of the receding die in order to modify the density of the solid cylindrical briquette. The material is first ground to minute particles, then fed to the tapered feed screw, and pressed through a die and through a rotary slotted head, 15 the latter of which forms the compressed material into a continuous spiral layer. The spiral layer or lamination has a width equal to the radius, or one half the diameter of the cylindrical die and cylindrical mold, and the finished 20 briquette is thus formed of spiral laminations which strengthen and reinforce the body structure of the briquette.

The sap, resin, pitch, and other moisture present in the sawdust or other material is expressed 25 from the particles of the material, and this moisture is used as an internal binder for cementing together the particles as well as the continuous laminations of which the briquette is formed. The tapered formation of the feed screw is instrumental in generating internal friction with 30 consequent internal heat in the moist material of the briquette to assist in utilizing the moisture as a binder, and means are provided for cooling the molds to prevent excessive heat therein.

The cylindrical molds are mounted to revolve, with an intermittently rotating mold wheel or 35 rotary carrier arranged transversely of the axis of the press or of the tapered feed screw, and the rotary carrier is interposed between the stationary die and feed screw at one side, and the hydraulically receding die at its other side. When all of the molds of the rotary carrier have 40 been filled with compressed briquettes, these briquettes are successively delivered from their molds by pressure feed of the tapered screw through the briquette-core, as the latter is forced from the stationary die into a mold that is occupied by a previously formed briquette. Means 45 are provided for severing the briquette and means are also provided for trimming the opposite ends of the finished briquette in order that they may be of uniform length.

The parts of the briquetting machine are compactly arranged to occupy a minimum space, and 50 the parts co-act to insure a continuous performance, with a high rate of production, at a very low cost. The invention consists in certain novel combinations and arrangements of parts 55 for carrying out the above purposes and per-

forming the functions set forth, as will herein-after be more fully set forth and claimed. In the accompanying drawings I have illustrated one complete example of the physical embodiment of my invention, which is in successful operation, in which the parts are combined and arranged according to the best mode I have thus far devised for the practical application of the principles of my invention. It will be understood that changes and alterations may be made in the exemplified structure, within the scope of my appended claims, without departing from the principles of my invention.

Figure 1 is a view in side elevation, with parts broken away for convenience of illustration, 15 showing the compactly assembled machine.

Figure 2 is an enlarged, longitudinal, vertical, sectional view, showing the formation of a briquette in its mold, and illustrating the tapered feed screw, and the yielding-resistance die receding against yielding, hydraulic pressure, the 20 position of the parts indicating the removal of a pressed briquette by a briquette in formation, from the mold.

Figure 3 is an enlarged sectional detail view 25 showing the feed screw, compression chamber of the fixed die, and the spaced slotted extension-head of the feed screw, the latter in elevation.

Figure 4 is a detail view partly in elevation 30 and partly in section, showing the rotary mold carrier with water cooling jacket for the molds, and the axial and radial water-passages therefor.

Figure 5 is a side elevation, partly in section, 35 of the rotary mold carrier, showing the water-cooling system for the molds and part of the ratchet mechanism for intermittent rotation of the carrier.

Figure 6 is a detail elevation of the ratchet mechanism for intermittently revolving the carrier, and Figure 7 is a detail view of the triplicate pawls and their holder forming part of the ratchet mechanism.

Figure 8 is a detail view of the rotary carrier showing the stationary detaching plate or abutment for the completed briquette and Figure 9 40 is a perspective view of the abutment, removed.

Figure 10 is a perspective view of one of a pair 45 of trimming knives or cutters, one for each end of the briquette.

Figure 11 is a longitudinal, horizontal sectional view showing the roller thrust bearing for the main conveyer, or feed-screw shaft, and showing also the driven sprocket of the sprocket-drive for the shaft.

Figure 12 is a broken, enlarged, detail view, 50 partly in section and partly in elevation, illustrating parts of the yielding die which offers hydraulic resistance to the briquette as it is being formed.

Figure 13 is a top plan view, on a smaller scale, of the cylinder and guides for the hydraulic mechanism of Figure 12.

Figure 14 is a view in side elevation, showing particularly one of the racks employed to advance or forwardly feed, the yielding resistance die.

The completed briquette B, which is fashioned from a core B', (see Figures 2 and 3) is a solid, cylindrical body, formed of a continuous layer or ribbon, laid in spiral formation against preceding laminations, and the briquette is formed, and cooled, in one of the numerous cylindrical molds 1 mounted near the outer periphery of the rotary mold carrier, or mold-wheel, indicated as a whole by the numeral 2.

The material for the briquettes is fed through the vertical chute 3 (Figure 1) from a suitable hopper (not shown) to the screw-conveyer or tapered feed-screw 4, which revolves within the feed chamber 5 of the inner mold or shell 6, which is fixed within the stationary housing 7. As shown, the interior bore of the mold 6 is fashioned in the shape of a truncated cone, tapering from its large end (into which the chute feeds the material) toward its outlet end, where a first-compression chamber 8 is provided, which terminates in a cylindrical extension, forming a second compression chamber 9 as well as a restricted discharge port for the core B' as the latter is in process of formation.

The forward end of the feed screw is fashioned with a central socket 10, in which is fitted a double-taper spindle 11, and the spindle is secured in the socket by means of a key 12. On the outer end of the spindle is fashioned a circular disk or die-head 13 in which is fashioned a transverse, inclined, slot 14, which extends inwardly from the periphery of the die-head. One face of this head is provided with a cutting edge 15 that extends along the slot 14, and the other face of the head is fashioned with an inclined or spiral cam-portion 16.

Thus the head 13 forms the front wall or abutment of the first compression chamber 8, and as the head 13 revolves with the feed screw, the material, which revolves with the feed screw, is pressed into a non-rotating mass in the first compression chamber between the smaller end of the feed screw and the head 13. The continuous revolutions of the feed screw gradually feed the material into the smaller threads of the screw, and the material is gradually pressed into smaller, compact, formation against the resistance of the head 13.

While the material in its first stage of compression remains stationary in the chamber 8, the cutting edge 15, as it revolves, slices off a continuous layer or ribbon, and directs this ribbon through the diagonal slot 14. As the ribbon emerges from the slot, it rides up the circular cam face 16 of the head at the side opposite to that of the slicing cutter 15, and this cam face 16 performs the second stage of compression for the core B' in the stationary mold 9 and in the moving mold 1.

To provide resistance for the second stage of compression, I first fill all of the molds with a dummy briquette, i. e. a solid cylindrical wooden block the size and shape of the briquettes to be made, and as the mold carrier revolves these dummies are successively discharged from their molds, until all of the molds 1 are filled with briquettes. The dummy-briquettes, are of course

used only at the start of the machine, and are then laid aside for future use.

When all of the molds are filled with briquettes, the succeeding briquettes are fashioned from cores, as B', and as indicated in Figure 2, the core B' forces the briquette B from its mold 1, and the core is forced or pressed from the second compression chamber or mold 9 and into the mold 1, by the action of the compression face 16 of the head 13.

Thus in the formation of the briquette, the feed screw presses the material into chamber 8 in a spiral layer approximating one half inch in thickness, then the cutter slices the material into a ribbon of approximately five-sixteenths of an inch thick, which is passed through the slot 14, and the compression face 16 then presses the lamination to approximately one-eighth of an inch in thickness, to form the solid cylindrical briquette.

After numerous tests I find that this two-stage compression of the briquette is necessary to produce a briquette of the desired and required density of a solid fuel that will not quickly disintegrate in the fire. I also find by tests that it is impossible to thus solidly compress the briquette by means of the tapering feed-screw alone, for the reason that it is not practicable to make the threads at the smaller end of the screw of sufficient strength to withstand the pressure that is required in the formation of the solid fuel. This great pressure is necessary to generate, by friction, the required heat by means of which the resins, oils, sap &c of the wood bind the material into the solid briquette. The ribbon, under its first stage of compression, enters the second compression chamber, and the rotary "wiping" action of the cam-face 16 of the head is instrumental in imparting the required pressure to create the friction and heat to bind the briquette as it is being formed.

Although, as hereinafter described, the action of the screw-feed, as well as the action of the rotary wheel or mold carrier, is intermittent, the pressure applied in the two stages of compression is continuous, i. e. the material in the two compression chambers is always under compression. This I find to be necessary, to overcome and eliminate any action due to the resilience of such woods as white pine, white fir, red fir, and other coniferous woods.

As shown in Figures 2 and 3, the spindle 11 has the threaded end of a retaining rod 17 secured therein, within the feed screw, and this rod, which extends through the tubular feed shaft 18, may be turned by nut 19 (Figure 11) to draw or pull the tapered spindle into its socket.

The tubular feed shaft 18 is a revolved from the motor (Fig. 1) 20 and its sprocket, through the sprocket belt 21 to the larger sprocket 22 on the shaft, and as the screw head or feed screw 4 is threaded on the boss or reduced extension 23 of the shaft, the feed-screw revolves with the shaft. In Figure 11 a single bearing block 24 is provided for the shaft 18, and in the block two annular, radial bearings 25 and 26 are provided, with an intermediate, end-thrust bearing 27 against the bearing ring 28. The ends of the bearing block are closed by means of plates as 29, 29, and it will be understood that the shaft and the feed screw turn anti-clockwise, in the bearings.

The complete briquette B, and the core B', are forced or pressed through the stationary mold 9

and the movable mold 1, against a yielding resistance or yielding, opposed, pressure, by means of the rotary cam-head, and for this purpose of 5 yieldingly resisting the pressure on the core and briquette, I provide an axially alined head or abutment 30 on the end of a reciprocable piston stem 31 which stem is secured to the piston 32 in the hydraulic cylinder 33.

As best indicated in Figures 4 and 12, the head 10 30 at the end of its forward stroke, i. e. to the left in the drawings, stops short of the near side of the rotary carrier 2 and the near ends of the molds 1 of the carrier, but the head is moved sufficiently near to the alined mold 1 so that the 15 far ends of the starting-dummies and the far ends of the succeeding briquettes B may successively be pressed against the outer face of the head 30.

Thus it will be evident in Figure 2 that the 20 completed briquette B is clamped at its ends between core B' and the head 30, and the briquette is being pressed or forced to the right, for delivery, as the head 30 yields to the pressure, or recedes from the mold 1. When the rear end of the 25 briquette B has moved to position clear of the mold 1 and the carrier 2, the rotation of the shaft 18 stops, the briquette is released from the core B' (which core has now become a briquette) and the head 30, and the briquette B drops into a 30 waiting receptacle (not shown).

The hydraulic cylinder 33 (Figures 1 and 12) is provided with two spaced oil pipes 35 and 36 communicating with ports 34 at the opposite ends of the cylinder and at opposite sides of the piston 35 in the cylinder, and oil is supplied to the cylinder from the oil supply pipe 37 which is connected with the supply tank 38.

By means of a regulating valve 39 in the connecting pipe line 37 which extends between the 40 two pipes 35 and 36, the movement of the oil from the cylinder at the rear side of the piston 32 may be varied. Thus the yielding resistance of head 30 to the core B' and the briquette B may be varied, a slow movement of oil from the cylinder affording a high resistance, and a more rapid movement of the oil from the cylinder affording a lower resistance. By varying this resistance the density of the solid briquette may be varied.

After the yielding head 30 has receded and a 50 completed briquette has been dropped or delivered, the head 30 is moved to the left in Figures 1 and 12 by positive mechanical action, and the oil is forced out of the cylinder by the piston 32, through pipe 35 and back through pipe 36 to the 55 rear of the piston. This return movement or feed of the yielding head 30 is accomplished with power from an electric motor 40, through reducing gears in the gear case 41 and a link belt drive 41a to the gear 41' in the case 42, to the power shaft 43, which is journaled transversely of the piston stem 31, in a plane below the stem, as indicated in Figures 12 and 14. The power shaft is provided with a pair of rackgears 44, spaced apart as indicated by dotted lines in Figure 13, and each gear engages with a rack 45 on the underside of a longitudinally extending guide rod 46 arranged parallel with, and at opposite sides of the piston stem 31 and the head 30.

These guide rods move with the piston stem 70 and piston, and they slide in the guides 47 projecting laterally from the cylinder 33 and located in pairs at the opposite ends of the cylinder. A cross head 48 extends transversely of the piston stem, and this head is fixed to the two guide rods 75 and to the central piston stem to form a rigid

structure that reciprocates as a unit in the formation of the briquette, and in its discharge.

The rotary mold carrier or mold wheel 2, as seen in the drawings is interposed between, and it rotates transversely of the feed-screw and the yielding resistance mechanism or head 30, and this carrier is intermittently revolved to bring successive molds 1, containing a briquette, between, and into axial alinement with the core B' and the head 30, and means are provided for retaining the carrier in rigid stationary position while a briquette is being forced out of its mold and a succeeding briquette is being forced into the same mold.

A large number, thirty, more or less, of the 15 molds 1 are mounted transversely of the carrier, and these molds or metal cylinders 1 are fixed in the side plates 49 and 50 of the circular carrier.

An annular water jacket, comprising a rim or outer ring 51 and an inner ring 52, is supported 20 between the side plates, and a central, circular partition 53 is employed to reinforce the carrier structure.

As best seen in Figure 5, an interior, transversely extending partition 54 divides the annular water chamber or jacket which surrounds all of the molds 1, and two series of spaced baffle plates 25 55 and 56, one series projecting outwardly from the inner ring and the other series projecting inwardly from the outer ring, are interposed in 30 the water chamber or jacket to impede the direct flow of water through the jacket, and to direct the flow into contact with the exterior surfaces of the molds 1.

The cooling water for the molds enters the 35 water jacket at the right of the partition 54 (Figure 5) and the water, after flowing in one direction around the interior of the jacket, leaves the jacket at the left side of the partition 54. Water is supplied to the jacket through the 40 inlet pipe 58, and passes from the jacket through outlet pipe 59, passing through ports in a central hub 60 of the carrier, which hub is fixed to the complementarily ported shaft 61 of the carrier. A supply pipe 62 receives water from 45 a suitable source and conveys the water to the axial passage 61a of the shaft 61, which passage communicates with the inlet ports of the shaft and hub, and a return pipe 63 receives the water from a complementary pair of ports, and a 50 passage in the shaft 61, and returns the water to its source for cooling, thus providing an endless circulation for the water to the water jacket.

Thus each briquette makes one complete revolution with its mold and carrier, and during 55 this revolution the briquette is subjected to a cooling treatment that is necessary to reduce the temperature of the briquette, caused by heat created by friction in the pressing process of the briquette.

The side plates, the molds, the water jacket, and other parts of the carrier may be welded together, or secured in other suitable manner, and the side plates and central partition of the carrier are secured to the central hub 61 of the 65 shaft, and the latter is mounted to revolve in its bearings 64, arranged at opposite sides of the hub, and these bearings are supported in the frame F.

The rotary carrier is located so that the low- 70 ernost mold 1 may be axially alined with the feed-screw and the yielding head and the rotary carrier is intermittently rotated or revolved through the use of an annular rack or tooth-ring 65, which is mounted on and encircles the ring 75

or rim 51 of the carrier. A lateral wear ring 66, which is replaceable when worn, is mounted at one side of the rack ring to close the notches of the teeth, and to guide and retain against 5 lateral movement, a number of pawls (here shown as three) 67, 68, and 69. These pawls are each pivotally mounted, as at 70 70a and 70' on a holder 71 (Figures 6 and 7), and springs 72 hold the pawls in operative position for engagement with the complementary teeth of the 10 rack ring.

The upright holder 71 is located adjacent the rack ring, and it is pivotally mounted, as by a pivot 70a, on a horizontally disposed ratchet lever 15 73, which is pivoted at 74 on the frame F at one side of the carrier. As indicated by dotted lines in Figure 6, the lever is oscillated by the employment of hydraulic pressure, and through this oscillation, the pawls intermittently revolve 20 or rotate the carrier anti-clockwise in Figure 6.

The lever is lifted, on its upstroke or idle stroke by means of a stem 75 pivoted at 76 to the free end of the lever, and this stem has a piston or plunger head (not shown) that reciprocates in the hydraulic cylinder 77. The hydraulic cylinder is also adapted to oscillate and for this purpose the cylinder is pivoted on its trunnions 78 in the brackets 79, to insure smooth operation of the rotating mechanism for the 25 rotary carrier. Oil under pressure is conveyed to the cylinder through inlet pipe 80 from a pump 81, which pump is operated from an electric motor 82, and the outlet pipe 83 from the cylinder is connected to said pump as shown.

30 35 The pump 81, which may be replenished with oil from the supply tank 38, which tank is provided with a manually operated cut-off valve 84, and the flow of oil to the hydraulic cylinder 77 is controlled by an automatically operating valve 85. The valve 85 is intermittently operated by means of an electro-magnet or air valve 86, and this magnetic control valve and the motor 82 are electrically connected in an operating circuit with the motors 20 and 40 in order that the 40 45 prime movers of the press, the yielding resistance mechanism and the operating mechanism of the rotary carrier are under the same electric control, and their movements synchronized, to render the entire machine automatic in its operation.

In Figures 8, 9, and 10, especially, will be seen the means for trimming the ends of the briquettes, and also the discharge or delivery means for the trimmed and completed briquette.

50 55 After the core B' has been fashioned to its full length, its opposite ends project or protrude from the opposite ends of the mold 1, and these projecting ends are to be cut off to insure uniformity in the length of the completed briquette B. For cutting or trimming the ends of the core I provide two complementary cutters or trimming knives 87, each provided with an attaching flange 88 by means of which it is bolted within an arcuate housing 89 of U-shape in cross 60 65 section, and the housing is bolted to the frame F.

These trimming knives are located at opposite sides of the rotary carrier in position so that the molds will pass between them carrying a briquette core, and as each knife is disposed 70 in the path of movement of one of the projecting ends of the briquette-core, the ends of the core are sheared off as the moving core engages and passes the knife.

75 After having had its ends trimmed, the briquette continues its travel during one revolution

of the carrier, anticlockwise in Figure 8, and the lowermost briquette, after having been trimmed, is clamped between a core B' and the yielding head 30, as heretofore described.

When the briquette is delivered, discharged, or 5 pushed from the mold by the succeeding core B', the cessation of screw-feed and the yielding movement of the head 30 permit the completed briquette to be released and the latter drops into 10 a receptacle, or is disposed of in other suitable 15 manner. Should the briquette have a tendency to stick to the following core, or to stick to the head 30, it is dislodged and forced to fall away from the rotary carrier or its mold by coming 20 in contact with a stationary abutment 90. This abutment is in the form of a plate that is bolted to the frame F and spaced a sufficient distance away from the rotary carrier to permit the untrimmed cores B' to pass thereby. But the plate, which has an end recess 91 of semi-circular shape 25 complementary to the circumference of the core or briquette, is located in position to obstruct any movement of the briquette should the latter be stuck to the core or to the head, and this obstruction causes the briquette to be dislodged from the core.

The capacity of the machine may be varied by the number of molds in the rotary carrier. For instance, while I have indicated approximately 30 molds in the carrier, this number may 30 be increased within limits as to the circumference or diameter of the rotary carrier, but in all cases the circumference of the carrier will be sufficient to permit a cooling period for each briquette that will cool and set the briquette to 35 insure its permanency. The screw-feed motor, and the other prime movers, may be adjusted to operate intermittently at periods of thirty seconds, and thus, after the machine has started the manufacture of the briquettes, one complete 40 briquette is delivered each thirty seconds.

In order to press all of the resiliency from the wood particles or material, and form a solid, rigid, briquette, I find that an exceedingly high, two-stage, pressure, is required as heretofore described. This high pressure, due to friction creates a high degree of temperature in the briquette, and therefore the pressure must be predetermined and limited in order to prevent burning of the briquette. Furthermore, the high degree of temperature of the pressed briquette must be eliminated during its process of manufacture and before the final delivery of the finished briquette. Therefore, the briquette is cooled while still in its mold and rotary carrier, and the cooling step is imparted to the briquette with facility, and without loss of time.

The machine as illustrated in the drawings is in actual operation, manufacturing the briquettes at comparatively low cost of production, and producing the finished product in large numbers ready for the furnace, stove, or other combustion devices.

Having thus fully described my invention, what I claim as new and desire to secure by Letters Patent is:—

1. In a briquette machine, the combination with a feed-screw and an aligned stationary mold, of a movable mold aligned therewith, a reciprocable yielding-resistance head aligned with the latter mold, and adapted to reciprocate exterior thereof of separate means for operating the feed screw, the movable mold, and the head, and means for synchronizing the operation of said means.

2. In a briquette machine, the combination with

1. A feed mechanism and an aligned stationary mold, of a movable mold aligned therewith, a yielding-resistance head aligned with the latter mold, and adapted to reciprocate exterior of the mold separate electrical motors acting as the prime movers for operating the feed mechanism, the movable mold and said head, and means for synchronizing the operation of said electric motors.
2. In a briquette machine, the combination with feed mechanism and an aligned stationary mold, of a movable mold adapted to receive material from the stationary mold, a reciprocable yielding-resistance head aligned with the movable mold, means for moving said head to within a spaced distance from the movable mold, and means for imparting a yielding resistance to said head.
3. In a briquette machine, the combination with feed mechanism and an aligned stationary mold, of a movable mold aligned with the stationary mold, a reciprocable yielding-resistance head aligned with the movable mold, positively acting means for moving said head to within a spaced distance from the movable mold, and means for imparting a hydraulic yielding-resistance to said head on its return movement.
4. In a briquette machine, the combination with feed mechanism and an aligned stationary mold, of a reciprocable yielding-resistance head aligned with said mold, and means for moving said head within a spaced distance of said mold, and means for imparting a yielding-resistance to said head on its return stroke.
5. In a briquette machine, the combination with feed mechanism and an aligned stationary mold, of a reciprocable yielding-resistance head aligned with the movable mold, means for moving said head to a point adjacent to but exterior of the adjoining end of the movable mold to receive a briquette, means for imparting a yielding resistance to said head on its return stroke, and means for varying the resistance of said head.
6. In a briquette machine, the combination with a feed-screw and means for intermittently operating said screw, of a rotary carrier, a series of molds in said carrier, means for intermittently operating said carrier, a reciprocable yielding-resistance head, means for intermittently operating said resistance head exterior of the mold but adjacent the adjoining end thereof, and means for controlling said several operating means, as described.
7. In a briquette machine, the combination with a stationary mold, of a movable carrier, a series of molds in said carrier and means on the carrier for cooling briquettes in the molds, and a reciprocable head movable exterior of the mold for co-action with said molds in the formation of the briquettes.
8. In a briquette machine, the combination with a stationary mold, of a movable carrier, a series of molds in said carrier and means on the carrier for cooling briquettes in the molds, and a reciprocable head movable exterior of the mold for co-action with said molds in the formation of the briquettes.
9. In a briquette machine, the combination with a feed mechanism and an aligned stationary mold, of a rotary carrier, a series of molds in said carrier adapted to align successively with the stationary mold, means on the carrier for cooling briquettes in said series of molds, and means co-acting with said molds in the formation of the briquettes.
10. In a briquette machine, the combination with an aligned feed-screw, stationary mold and reciprocable head, of a transversely arranged rotary carrier interposed between said stationary mold and head, a series of molds mounted in said carrier, and means on the carrier for cooling briquettes within the molds of the carrier.
11. In a briquette machine, the combination with feed mechanism, a stationary mold and a reciprocable head, of a transversely arranged rotary carrier interposed between said mold and head, a series of molds mounted in said carrier, a water jacket enclosing said series of molds, and means for circulating water through said jacket.
12. In a briquette machine, the combination with feed mechanism, a stationary mold, and a reciprocable head, of a rotary carrier having a series of molds therein, a water jacket enclosing said series of molds, a dividing partition in the jacket, inlet and outlet water-pipes at the sides of said partition, and means for supplying water to said inlet pipe.
13. In a briquette machine, the combination with feed mechanism, a stationary mold, and a reciprocable head, of a transversely arranged rotary carrier interposed between said mold and head and a series of molds in said carrier, and stationary cutters at opposite sides of the carrier for severing the ends of briquettes carried in the molds of said series.
14. In a briquette machine, the combination with feed mechanism, a stationary mold, and a reciprocable head, of a transversely arranged rotary carrier interposed between said mold and head, a series of molds in said carrier, a water jacket mounted in the carrier and enclosing said series of molds, and stationary cutters at opposite sides of the carrier for severing the protruding ends of briquettes carried in said series of molds.
15. In a briquette machine, the combination with feed mechanism, a stationary mold, and a reciprocable head, of a rotary carrier, a series of molds in said carrier and means for bringing successive molds of the series in alignment with said stationary mold and head, a water jacket mounted in the head and enclosing said series of molds, stationary cutters at opposite sides of the carrier for severing protruding ends of briquettes in said series of molds, and a stationary abutment for obstructing movement of a completed and cooled briquette.
16. In a two-stage compression briquette machine, the combination with a housing forming a feed-chamber and feed mechanism therein, a feed-head rigid with and spaced from said feed mechanism to form a first-compression chamber, of a mold aligned with said head, and a reciprocable head aligned with said mold and movable exterior thereof to form a second-compression chamber.
17. In a two-stage compression briquette machine, the combination with a housing forming a feed chamber and mold, of a feed-screw in said chamber, a compression head mounted on and spaced from said screw to form a first-compression chamber in said mold, a movable mold aligned with said screw, and a reciprocable head longitudinally aligned with the movable mold and movable exterior thereof to form a second-compression chamber between the compression head and the reciprocable head.
18. In a two-stage compression briquette machine, the combination with a housing forming a feed chamber and mold, of a feed screw in the housing, a compression-head mounted on and spaced from said screw, said compression head having a slot therein, a cutter at one side of the head and a cam face at the other side of the head, a movable mold aligned with said screw and head, and a reciprocable head aligned with said compression head.
